UNITED STATES PATENT OFFICE.

EDWARD J. BROOKS, OF EAST ORANGE, NEW JERSEY.

OPEN-FACE SLEEVE SEAL.

Application filed March 13, 1924. Serial No. 698,937.

To all whom it may concern:

Be it known that I, EDWARD J. BROOKS, a citizen of the United States, and a resident of East Orange, in the county of Essex and State of New Jersey, have invented certain new and useful Improvements in Open-Face Sleeve Seals, of which the following is a specification.

This invention relates to a sleeve seal used to lock overlapping ends of metallic strapping, and has more particularly reference to an improvement upon the seal disclosed in application Ser. No. 543,789 filed March 14, 1922, the object of the improvement being to facilitate the process of forming the seal around the strap ends.

In the accompanying drawings the invention is disclosed in a concrete and preferred form in which

20 Fig. 1 is a perspective view of the sealing member.

Fig. 2 is a sectional view showing overlapped strap ends and the sealing member in straddled position thereto.

25 Fig. 3 is a sectional view showing the wings of the seal bent beneath the strap ends.

Fig. 4 is a diagrammatic view showing the tightening step of the sealing operation.

30 Fig. 5 is a sectional view showing the strap ends and seal interlocked.

Fig. 6 is a plan view of the finished seal.

The open face seal member 1 consisting of a main portion 2 and upstanding wings 3 is placed over the overlapped strap ends 4 and 5, as shown in Fig. 2, between the dies of a tool such as is shown in application Ser. No. 543,789 filed March 14, 1922.

The tool is then actuated part way to fold the wings beneath the strapping as indicated in Fig. 3. After this the strap ends are tightened as indicated in Fig. 4 by means of the arrows, and finally the tool is actuated all the way to crimp the metal of the seal and strapping as indicated in Figs. 5 and 6.

If main portion 2 is absolutely horizontal as in the application previously referred to there is, at times, difficulty in directing the bending movement of the wings 3 from the position they occupy in Fig. 2 into the position shown in Fig. 3. I have found that, by making main portion 2 concavo-convex with its convexity extending in the same direction as upstanding wings 3, the difficulty set forth above may be obviated. For it will be understood, the upper die of the tool will first strike the main portion at the point of bend of the wings, this action tending to render said main portion more nearly horizontal and this in turn forcing the lower ends of the wings inwardly beneath the strapping.

I claim:

An open face sheet metal seal comprising: 65 a main portion provided with an upstanding wing at each side, both of said wings extending in the same direction and the main portion forming a concavo-convex bridge 70 between the wings, the convexity of said main portion extending in the same direction as the upstanding wings.

Signed at New York city in the county of New York and State of New York this 7th day of March, 1924.

EDWARD J. BROOKS,
